UNITED STATES PATENT OFFICE.

FREDERICK C. LAMBERT, OF NEW YORK, N. Y., ASSIGNOR OF ONE-HALF TO GEORGE J. KOCH, OF NEW YORK, N. Y.

WIND-SHIELD FOR MATCH-BOXES.

1,094,225.

Specification of Letters Patent. Patented Apr. 21, 1914.

Application filed October 24, 1913. Serial No. 797,053.

To all whom it may concern:

Be it known that I, FREDERICK C. LAMBERT, a citizen of the United States, and a resident of the city of New York, borough 5 of the Bronx, in the county and State of New York, have invented a new and Improved Wind-Shield for Match-Boxes, of which the following is a full, clear, and exact description.

10 The object of the invention is to provide a new and improved wind shield arranged for convenient attachment to match-boxes such, for instance, as contain safety matches in a drawer slideable in a casing, the wind 15 shield when not in use folding onto the casing, and when extended for use permits of safely igniting a match for lighting a cigar or other article or device.

In order to accomplish the desired result 20 use is made of an attaching member adapted to be passed between one side of the casing and the adjacent side of the drawer, and a shield hinged on one end of the said attaching member and having a back and side 25 wings extending from the back and fitting exteriorly onto the front and rear of the casing.

A practical embodiment of the invention 30 is represented in the accompanying drawings forming a part of this specification, in which similar characters of reference indicate corresponding parts in all the views.

Figure 1 is a perspective view of the wind 35 shield as applied to an ordinary safety match box and shown extended or in open position; Fig. 2 is a similar view of the same with the wind shield in folded or closed position; Fig. 3 is a sectional side elevation of the same; Fig. 4 is a plan view of the same; 40 and Fig. 5 is a perspective view of the wind shield.

The wind shield A is shown applied to a match box B having a casing B' and a drawer B² slideable in said casing B' and 45 containing safety or other matches C, as plainly indicated in Fig. 3. The wind shield A comprises an attaching member A', preferably in the form of a plate connected at one end by a hinge or pivot A² with one 50 end of a shield back A³ from which extend approximately at right angles two wings A⁴ fitting exteriorly on the front and rear of the casing B' of the match box. The attaching member A' fits on the inner face 55 of one of the sides of the casing B' and

thus extends between the said casing side and the adjacent side of the drawer B², as will be readily understood by reference to Fig. 3. In order to hold the attaching member A' in position in the casing B' the free end of the attaching member A' is provided with an outwardly-extending flange A⁵ fitting onto the corresponding edge of the casing side, as shown in the drawings. It is understood that the attaching member A' is approximately of a length corresponding to that of the side of the casing B'. The back A³ of the wind shield is provided near its pivotal end with front openings A⁶ to permit air to pass into the wind shield when the latter is in open position, as shown in Fig. 1.

In order to apply the wind shield to the match box the drawer B² is preferably drawn out of the casing B' and then the attaching member A' of the wind shield is passed into the casing and fitted against one side of the casing, after which the drawer B² containing the matches C is replaced in the casing B'. Normally the wings A⁴ overlie the outer faces of the front and rear of the casing B' so as to present no undesirable obstruction on the match box. When it is desired to use the wind shield the user swings the shield outward into open position, as shown in Fig. 1, so as to form a chamber between the wind shield and the corresponding side of the casing B'. The user now strikes the match on the ignition face of the inclosed side of the match box B' so that the lighted match is contained in the chamber formed by the shield A and the match box B, and the user can now light a cigar, cigarette or the like from the lighted match by passing the butt end into the said chamber. From the foregoing it will be seen that the match is shielded while being ignited on the igniting surface of the side of the match box and the lighted match is shielded for safely lighting a cigar, cigarette or other article.

In practice, the wind shield A' is preferably made of sheet metal and hence can be manufactured very cheaply and readily applied to the ordinary match box as mentioned.

It is understood that when the matches C have been used up in the match box the wind shield is detached from the match box and the latter can be thrown away, and the

wind shield can be applied to a filled match box in the manner above described and shown in the drawings.

Having thus described my invention, I claim as new and desire to secure by Letters Patent:

1. A wind shield for use on a match box having a casing and a drawer slideable in the casing, comprising an attaching member adapted to engage the inner face of one of the sides of the casing, one end of the attaching member having a flange engaging one edge of the casing side, and a shield having a back and wings extending at right angles from the back, and a hinged connection between one end of the said shield back and the other end of the attaching member, whereby to permit the wings of the shield to be adjusted upon the exterior surfaces of the casing front and rear, said shield back being provided with draft openings, adjacent the hinged connection, all for the purpose described.
2. A wind shield for use on a match box having a casing and a drawer slideable in the casing, comprising an attaching member

adapted to engage the inner face of one of the sides of the casing, one end of the attaching member having a flange engaging one edge of the casing side, a shield having a back and wings extending at right angles from the back, and a hinged connection between one end of the said shield back and the other end of the attaching member, whereby to permit the wings of the shield to be adjusted upon the exterior surfaces of the casing front and rear, said shield back being provided with draft openings, adjacent the hinged connection, all for the purpose described.

In testimony whereof I have signed my name to this specification in the presence of two subscribing witnesses.

FREDERICK C. LAMBERT.
